JOHN P. HAYES, OF PHILADELPHIA, PENNSYLVANIA.

Letters Patent No. 82,311, dated September 22, 1868; antedated September 8, 1868.

IMPROVEMENT IN RANGES.

The Schedule referred to in these Letters Patent and making part of the same.

TO ALL WHOM IT MAY CONCERN:

Be it known that I, JOHN P. HAYES, of the city of Philadelphia, in the State of Pennsylvania, have invented a new and useful Improvement in Ranges for cooking and warming; and I do hereby declare that the following is a full, clear, and exact description of the construction and operation of the same, reference being had to the accompanying drawings, making a part of this specification, in which—

Figure 1 is a front elevation of the said improved range, the doors having been removed.

Figure 2, a view of the back or rear of the same, as in connection with the brick-work, between the flues thereof.

Figure 3, a plan view of the upper side of the same, without its top plate.

Figure 4, a central vertical section of same, above the dotted line *v w* of fig. 3.

Figure 5, a central vertical transverse section of the same, on the left of the dotted line *x y* of fig. 3.

Figure 6, an enlarged top view of a sliding and removable portion of the fuel-grate; and

Figure 7, a side view of a draught-spreading check-plate, near the outlet of the oven-heating flue, and beneath the latter.

Like letters of reference indicate the same parts when in the different figures.

The object of my improvement is to facilitate the construction and location of the brick flues in setting the range; the removal of stones and cinders or clinkers from the incandescent fuel in the fuel-cylinder, without "putting out the fire;" and also, to increase the general cooking, baking, and air-warming functions of a range; and my invention consists in the peculiar constructions and combinations hereinafter set forth, described, and specified.

Referring to the drawings, A is the fuel-cylinder; B, a draught-chamber or tunnel communicating therewith; C, the air-heating chamber; D, the ash-pit; E, the sliding removable portion of the fire-grate; F, an air-heating space or chamber attached to one side of the fuel-cylinder A, and opening into the oven G; H, an air-deflecting annular plate above the fuel-cylinder A; I, the oven-heating draught-flue; J, an equalizing check-plate across the oven draught-flue I; K, a dead-flue in rear of the oven G; L, the escape-flue, from the bottom of the oven G; M, the fresh-air-supplying space; N N, the ribs, for guiding in the location and construction of the brick flues; O, a continuation of the escape-flue L from the bottom of the oven; P, the dust-flue from the ash-pit; Q, the direct flue from the fuel-chamber; and R, the hot-air flue.

The fuel-cylinder A is of cast iron, and rests upon a horizontal plate *c'*, over the ash-pit D, and communicates therewith through the usual grate, and has a flange around its upper edge, which fits in a recess in the edge, formed by a corresponding opening in another horizontal plate, *c''*; the two plates, *c'* and *c''*, forming the top and bottom of the air-heating chamber C, around the fuel-cylinder A. Around on the upper side of the plate *c''*, the air-deflecting annular plate H is fixed so as to leave a thin, open space between it and the upper edge or flange of the fuel-cylinder A, for the purpose of allowing the fuel-cylinder A to expand upward, and at the same time allow a sufficient opening to remain for the passage of a thin stratum of air from chamber C into the open upper end of cylinder A, for the combustion of inflammable gases arising from the incandescent fuel, (see figs. 3, 4, and 5.)

The front part of cylinder A has an open tunnel projecting forward from its lower end, and forming the hot-air draught-chamber B, its front end opening into the chamber C, and through an opening, *c'''*, in the plate *c'*, into the ash-pit D, (see figs. 4 and 5.) This chamber B is fitted with a detachable horizontally-sliding plate, E, which is grated at its inner half by bars *e'*, and has also a series of upright grate-bars, *e''*, near its mid-length, all constructed and arranged so that when the plate is pushed into its seat in the tunnel or chamber B, the bars *e'* will form part of the bottom grate of the fuel-cylinder A, and the bars *e''* a small upright grate in the front side of the same, or back end of the tunnel or chamber B, (see figs. 3, 5, and 6,) so that when this plate, E, is pulled forward and withdrawn, it will leave an opening for the discharge of cinders, clinkers, stones, &c., from the fuel-cylinder A, without "putting out the fire," whilst the said chamber, at all times, affords

ready access for prying up and loosening the fuel with a straight poker, and also the entrance of either hot or cold air, or both, into the cylinder A, as may be desired.

The air-heating chamber F forms a section of the fuel-cylinder A, and consists of a hollow cast-iron piece, opening at its upper end directly into the oven G, and at its lower end into the hot-air chamber C, in which it is placed, and also into the fresh-air-supplying space M below, so as to serve the purpose of conducting a current of pure warm air into the oven for ventilating it; an opening, with a slide attached, being made at g' for its eventual escape into the flue I, (see fig. 4.)

The check-plate J is a partition, fixed across the flue I, under the oven G, in the usual manner, but instead of making it closed at its upper and lower sides, as heretofore, I cut away a wedge-shaped portion from its upper side, so as to leave a gradually-increasing opening, j', thereat, for the purpose of spreading the hot-draught air and gases more uniformly over the lower plate or bottom of the said oven, (see figs. 1, 4, and 7.)

The draught-flue I, around the oven G, is widened off to one side, so as to produce a dead-flue, K, coextensive with the back of the oven, (see fig. 2,) for the purpose of more perfectly heating the whole back plate of the said oven.

The ribs N N are cast on the back plate or plates of the range, (see fig. 2,) for the purpose of guiding the bricklayer in locating and constructing the flues K O P R in a more ready and unmistakable manner, and therefore facilitating the work of setting the range, and enabling an inexperienced bricklayer to set the range in a perfect manner without any difficulty in this all-important point, in view of the proper operating of the range when in use.

It will be seen, as the open front end of the tunnel B does not extend forward to the front plate of the range, but communicates openly with the air-heating chamber C above, and also, through an adjustable opening, c'', in the plate c', with the ash-pit D below, that when the opposite outside door and the ash-pit door, in the front plate of the range, are closed, and the usual hot-air escape "registers," in the rooms of the building, left open, the heated air in the chamber c' will be continually drawn through the said tunnel B into the fuel-cylinder A, thus supporting the combustion of the fuel by heated air—an economical result; and also preventing any of the air heated in the chamber C from entering the said rooms—a very desirable and importantly useful result in hot weather.

It will also be seen that as the open mouth of the tunnel B is directly opposite to the outside door in the front plate of the range, free access can at any time be had to the tunnel, for withdrawing the sliding grate E, loosening or agitating the fuel in the cylinder A, by a straight poker, withdrawing the cinders, and discharging the latter and the accompanying ashes down into the ash-pit D with great facility, without causing any of the same to fall outside of the front plate of the range; and these results are the objects sought for and obtained in a perfect manner by the peculiar construction and arrangement of the parts specified.

It will also be seen that the construction of the air-heating flue F, and its arrangement in relation to the fresh-air space M, the air-heating chamber C, the fuel-cylinder A, and the oven G, as described, will ventilate the latter with fresh hot air, in a more rapid and effective manner than heretofore, without reducing the temperature of the oven; and the dead-flue K being made coextensive in height and breadth with the back plate of the oven G, as described, aids, in a more effective manner, in heating the said oven than the narrow draught-flue heretofore provided for the purpose, and is therefore of important utility, whilst the ribs N N afford facility and accuracy in "setting" the range never before afforded to the builder of ranges, and are, therefore, highly important and useful.

Having thus fully described my improvement in ranges, what I claim as new therein, and desire to secure by Letters Patent, is confined to the following:

1. I claim the construction and arrangement of the tunnel B, in its relation to the cylinder A and the air-heating chamber C, whereby the air for the combustion of the fuel in the cylinder can at any time be drawn from the air-heating chamber C, substantially as and for the purposes described.
2. The construction and arrangement, in relation to each other, of the tunnel B, the detachable sliding grate E, and the adjustable opening c'', in the plate c', into the ash-pit D, substantially as and for the purposes described.
3. The construction and arrangement of the air-heating flue F, in relation to the cylinder A, the air-heating chamber C, the cold-air space M, and the oven G, substantially as and for the purpose described.
